DESIGN FOR AN ESCUTCHEON PLATE FOR A RADIO RECEIVER

Clyde A. Peterson, Chicago, Ill., assignor to Wells-
Gardner & Co., Chicago, Ill., a corporation of
Illinois

Application November 10, 1943, Serial No. 111,641

Term of patent 3½ years

(Cl. D26—1)

To all whom it may concern:

Be it known that I, Clyde A. Peterson, a citizen of the United States, residing at Chicago, in the county of Cook and State of Illinois, have invented a new, original, and ornamental Design for an Escutcheon Plate for a Radio Receiver, of which the following is a specification, reference being had to the accompanying drawing, forming part thereof, in which—

Figure 1 is a front perspective view of the

escutcheon plate for a radio receiver showing my new design;

Fig. 2 is a front elevational view thereof; and

Fig. 3 is a front profile of a vertical sectional view taken on line 3—3 of Fig. 2.

I claim:

The ornamental design for an escutcheon plate for a radio receiver, as shown.

CLYDE A. PETERSON.
